United States Patent Office.

DAVID STUART AND LEWIS BRIDGE, OF PHILADELPHIA, PENNSYLVANIA,
ASSIGNORS TO STUART, PETERSON & CO., OF SAME PLACE.

Design No. 4,320, dated August 30, 1870.

DESIGN FOR A PORTABLE RANGE.

The Schedule referred to in these Letters Patent and making part of the same

We, DAVID STUART and LEWIS BRIDGE, both of Philadelphia, county of Philadelphia, State of Pennsylvania, have invented or produced a new and original Design for a Portable Range, of which the following is a specification.

The perspective view in the accompanying drawings illustrates our design for a range, which consists of a bottom plate, A, with projecting front edge, a top plate, B, with six boiler-holes, *a*, and outlet-opening, *d*, a front plate, D, with oven-opening *e*, grate-opening *f*, ash-pit opening *h*, an end plate, E, with register *i* and opening *j*.

The opposite end plate and rear plate may be plain, and therefore they have not been shown in the drawings.

The plates D and E and the exposed portion of the bottom plate A may be ornamented in any manner

which the taste of the constructor may suggest, the several openings being provided with suitable doors, which may also be ornamented in any desired style.

Claim.

A range, of the shape and configuration substantially as described and illustrated in and by the accompanying drawings.

In testimony whereof we have signed our names to this specification in the presence of two subscribing witnesses.

DAVID STUART.
LEWIS BRIDGE.
